(57) **CLAIM**

The ornamental design for a smart pill container, as shown and described.

DESCRIPTION

FIG. 1 is a top view of the first embodiment of the smart pill container.

FIG. 2 is a bottom view of the first embodiment of the smart pill container.

FIG. 3 is a front plane view of the first embodiment of the smart pill container.

FIG. 4 is a back plane view of the first embodiment of the smart pill container.

FIG. 5 is a right side view of the first embodiment of the smart pill container.

FIG. 6 is a left side view of the first embodiment of the smart pill container.

FIG. 7 is a perspective view of the first embodiment of the smart pill container.

FIG. 8 is a top view of the second embodiment of the smart pill container.

FIG. 9 is a bottom view of the second embodiment of the smart pill container.

FIG. 10 is a front plane view of the second embodiment of the smart pill container.

FIG. 11 is a back plane view of the second embodiment of the smart pill container.

FIG. 12 is a right side view of the second embodiment of the smart pill container.

FIG. 13 is a left side view of the second embodiment of the smart pill container; and,

FIG. 14 is a perspective view of the second embodiment of the smart pill container.

The broken lines depict portions of the article that form no part of the claimed design.

1 Claim, 8 Drawing Sheets
